Primary Examiner — R. Johnson(57) **CLAIM**

The ornamental design for an electric piano, as shown and described.

DESCRIPTION

FIG. 1 is a perspective view of an electric piano showing my new design.

FIG. 2 is a front view of an electric piano.

FIG. 3 is a rear view of an electric piano.

FIG. 4 is a left side view of an electric piano.

FIG. 5 is a right side view of an electric piano.

FIG. 6 is a top view of an electric piano.

FIG. 7 is a bottom view of an electric piano.

FIG. 8 is an enlarged view of the portion taken at line-8 in FIG. 2.

FIG. 9 is an enlarged view of the portion taken at line-9 in FIG. 6; and,

FIG. 10 is an enlarged view of the portion taken at line-10 in FIG. 3.

The broken lines in FIGS. 2, 3 and 6, encircling the enlarged views, are for illustrative purposes only and form no part of the claimed design.
